REGULATOR FOR OIL BURNERS

George W. Whitehurst, Portsmouth, Va.

Application December 5, 1933, Serial No. 701,078

7 Claims. (Cl. 238—6)

This invention relates to oil burners such as is shown in my copending application for patent Serial No. 701,077 filed of even date herewith, now Patent No. 1,983,111, and particularly to a heat 5 regulator for such a heater.

The general object of my invention is to provide means for regulating the heat supplied from an oil heater without the necessity of turning up or turning down the wicks of the heater or 10 manually opening or closing valves.

A further object is to provide a supply tank for the heater having a float controlled inlet valve and having a thermostatically controlled outlet valve with means for regulating the maximum and minimum outlet from said valve to any 15 desired degree.

Other objects will appear in the course of the following description.

The figure of the drawing shows an elevation 20 of a heater constructed in accordance with my invention, the reservoir or tank with its allied parts being in section.

Referring to this drawing, A designates a central or medially disposed chamber within which 25 is disposed a series of concentric combustion chambers designated B, the lower ends of these combustion chambers having burners C provided with wicks D. Disposed exteriorly of the central casing A are flue passages shown in elevation in 30 the figure and designated E whereby products of combustion are caused to circulate and pass out through a flue not shown, the spaces F between these flue passages E and the casing A extending from front to rear of the burner and permitting 35 the passage of air into the room through these spaces so that the air may be heated. This structure is fully disclosed in my pending application above referred to and, therefore, needs no further description.

40 Oil is supplied to the burner of the heater from an oil tank or reservoir designated 10. The bottom of this tank rests upon a fitting 11 having a branch 12 connected to the fuel supply pipe shown in dotted lines and designated 13. Having screw-threaded engagement with the bottom wall 14 of the reservoir 10 is a valve seat 15 which depends into the chamber 11 and is formed with inlet openings or passages 16.

For the purpose of holding the chamber 11 in 50 place against the bottom 14, a screw 17 is provided which extends up through the bottom of the chamber 11 and extends into the depending portion of the seat 15. By removing this screw, the chamber 11 may be removed from the reservoir 55 and then the seat may be removed.

The top of the reservoir is formed by a plate 18 which has a central guide aperture for a valve stem 19. This valve stem coacts with the seat 15 and is guided at its lower end by a guide 20. For the purpose of controlling this valve, I provide 60 a float 21 engaging against levers 22 whose inner ends engage within a flanged collar 23 carried by the valve stem 19.

It will be seen that with this construction when the float rises, the levers 22 will force the valve 19 65 downward, close the inlet aperture through the seat 15 and as the liquid within the reservoir 10 falls, the float will descend, permitting the pressure of the oil entering through pipe 13 to lift the valve until the proper height has again been 70 reached.

It will be understood, however, that an operative connection might be formed between the ends of the lever 22 and the float 21 to cause the upward movement of the valve 19 upon the downward movement of the float. 75

Disposed to one side of the reservoir 10 and cast as part of this reservoir, if desired, is a chamber 24, which, at its lower end, is formed with a valve seat 25 opening into a duct 26 extending laterally 80 from the bottom of the reservoir 10, this duct 26 being closed at its outer end by a plug 27. A screw 28 extends upward through the bottom of the duct 26, this screw having a shank 29 which may be manually turned to adjust the screw in 85 either direction, this shank passing through a gland 30. The upper end of the chamber 24 is constituted by a thimble or gland 31 having screw-threaded engagement with the walls of the chamber 24. Extending downward through this 90 gland and through the chamber 24 is a valve stem 32 having a valve 33 at its lower end coacting with the valve seat 25, this valve having at its lower end a pin 34 extending through the valve seat 25 and confronting the screw 28. The valve 95 stem 32 just below the cap 31 is formed with a shoulder 35.

Supported in brackets upon the plate 18 is a thermostat designated generally 36 which is shown as consisting of a coil or spiral of metal 100 or any other suitable material which will expand under heat and contract under cold and which is exposed to the air of the room. The outer end of this coil is transversely extended at 37 and supports the valve stem 32 bearing 105 against a bead 38 carried by the valve stem. The other end of this coil 36 extends down into a socket formed in an angular arm 39 which is mounted upon a pin or shaft 40 journaled in the bracket 41. Thus the arm 39 may rock. The 110

arm at its outer end is apertured for the passage of guide pin 42 extending upward from the plate 18, this aperture being considerably larger than the pin. A spring 43 urges the arm 39 upward 5 while a sleeve nut 44 has screw-threaded engagement with the pin 42 and bears against the upper face of the arm 39. By this means, the arm 39 may be forced downward or held upward to any degree required. As the arm 39 is 10 forced downward by the nut 44, it will cause the spring to turn in a clock-wise direction and force the arm 37 downward whereas when the nut 44 is loosened, the spring 43 will force the arm upward, thus causing the arm 37 to lift, 15 lifting up on the valve 42. When the temperature increases beyond a desired point, which point is regulated by adjustment of the nut 44, the arm 37 of the thermostat will move downward, permitting the valve stem 32 to move 20 downward toward a closing position, thus reducing the flow of oil to the wicks.

In order to prevent an entire closing off of the flow of oil to the wicks, the screw 28 is provided, which by adjustment limits the degree to 25 which the valve 33 may move toward the seat 25 so that there will always be at any time a small flow of oil to the wicks unless the screw 28 is fully retracted.

In order to prevent an excess opening of valve 30 33, a shoulder 35 is provided which stops the valve 33 on its upward movement at any desired setting of maximum oil flow, controlled by the setting of the gland 31.

A suction pipe 45 leads from the top plate 18 35 to one of the flues E. Irregular draft caused by high winds or from other causes acts through pipe 45 to cause a lift or upward pull on float 21 and also a lift on oil in reservoir 24 through vent 46 equal to the lift on the oil in the burner ring C. This causes an even oil flow by balancing pressure or suction. Pipe 45 also carries off the fumes within the tank 10.

The provision of the suction pipe 45 is of great 40 importance in securing an even draft. All oil burners are critical to oil supply because of the small proportion of oil to the great volume of air. A float valve and burner is adjusted in the heater with the service door open. The door being open, draft is relieved and oil will stay at a level. Shut the door, however, and immediately 45 the draft through the burner acts on the surface of the oil, raising its level and in a storm or high wind, the oil will keep surging and lifting until it reaches a level equal to the draft pull. By providing this suction pipe to the float chamber and having a connection 46 to the valve chamber 24, the excess draft, above what the unit is regulated for, is balanced. When excess draft occurs 50 above the normal setting, oil is lowered in the valve chamber. If this chamber is open to the atmosphere and the float valve works to keep this level constant, but the suction pipe 45 in my device also acts to lift the float and checks the oil flow so that upon a high draft, the oil 55 flow is checked and not increased and this makes the use of automatic dampers in the stove pipe unnecessary. The flare-up in oil burners is not from too much air, but from too much oil and I have found from actual experience that action 60 occurs as above stated and that by connecting the oil chamber or reservoir 10 and the valve chamber 24 up by the pipe 45 with the flue E that carries off combustion from the burners, the action of a high draft of air is balanced. 65

70 The draft no longer acts merely upon the burn-

ers causing more oil to be sucked in but also acts to prevent an overflow of oil and prevent, therefore, any flaring up of the oil burners due to too much oil.

The operation of this device will be obvious from what has gone before. There is always, as before stated, a small flow of oil to the wicks D so as to permit these wicks to burn with a low flame constituting a pilot light. As the temperature of the room decreases below the normal degree, the thermostat 36 will act to lift the valve 33 further away from its seat, permitting more oil to flow to the burners, thus securing a higher heat in the burners. If the heat of the room rises above a predetermined temperature, the expansion of the thermostat will cause the valve 32 to lower, thus reducing the flow of oil to the burner. The temperature at which the thermostat will act to increase or reduce the flow of oil to the burner may be accurately regulated by means of the screw 44 so that any desired heat may be maintained.

While I have illustrated certain details of construction and arrangements of parts, it will be understood that these may be varied in many 100 ways without departing from the spirit of the invention as defined in the appended claims.

I claim:—

1. Means for regulating the flow of oil to an oil burner, comprising an oil containing chamber 105 having an inlet, a float controlled valve controlling flow through said inlet, the chamber having an outlet, a vertically movable valve having a stem and controlling flow through said outlet, adjustable means for preventing the full seating 110 or opening of said valve, and thermostatically operated means for shifting said valve toward or from its seat including a thermostatic coil having an arm engaged with the valve, the inner end of the coil being mounted for oscillation and having an arm, a screw extending upward loosely through said arm, a spring urging the last named arm upward, and a nut engaging the screw and adjustable to force the last named arm downward against the action of said spring.

2. Means for controlling the flow of oil to a burner comprising an oil containing chamber having an inlet, a float operated valve controlling the inlet of oil to said chamber, the chamber having an outlet, a valve casing extending upward 125 parallel to one end of the chamber and communicating with said outlet and having a valve seat and communicating with the upper end of the chamber, a valve stem disposed in said valve chamber and having a valve coacting with the 130 seat, manually adjustable means for controlling the degree to which said valve can approach its seat, a resilient thermostatic coil mounted upon the chamber, the outer extremity of the coil being formed to provide an arm engaging the valve 135 stem, an arm engaged with the inner end of the coil and mounted for rocking movement, a screw extending upward from the upper wall of the chamber and passing loosely through the last named arm, a spring bearing against the last 140 named arm and urging it upward, and a nut mounted on the screw and adjustable to force the last named arm downward against the action of the spring.

3. In an oil burner, an oil containing chamber 145 operatively connected to the burner and having an inlet and an outlet, a float operated valve controlling the inlet of oil to said chamber, a valve casing extending upward parallel to one end of said chamber and communicating with said 150

- outlet and having a valve seat, said valve casing communicating with the upper end of the float chamber above the level of oil therein, a valve stem disposed in said valve chamber and having 5 a valve coacting with the seat, means for shifting said valve nearer to or further from the seat, a flue for the burner and a pipe connection from the upper end of the chamber to said flue whereby to secure equal suction on the flame in the 10 burner and oil in said chamber and in the inlet valve casing on both sides of the inlet valve.
4. In an oil heater having a burner enclosing casing and having a flue carrying off products of combustion from the burner, an oil reservoir 15 connected to the burner and having an inlet and an outlet, the outlet leading to the burner, a float controlled valve controlling the inlet of oil to the reservoir and a communicative connection between the upper portion of the reservoir and the 20 flue.
5. In an oil heater having a burner enclosing casing and having a flue therefrom carrying away products of combustion, an oil reservoir connected to the burner and having an inlet and an outlet, the outlet leading to the burner, a float controlled valve controlling the inlet of oil to the reservoir, a second valve controlling the flow from the reservoir to the burner, a valve casing therefor, the upper portion of the valve casing communicating with the upper portion of the reser- 25
- 30
- voir, and a communicative connection between the upper portion of the reservoir and said flue.
6. Means for regulating the flow of oil to an oil burner comprising an oil containing chamber having an inlet, a float-controlled valve therefor, a longitudinally movable valve having a stem and controlling flow through said outlet, and thermostatically operated means for shifting said valve toward or from its seat including a thermostatic coil having an arm engaged with the valve, the inner end of the coil being mounted for oscillation and having an arm, and screw means bearing against said arm and adjustable to oscillate the thermostat in one direction or the other. 80
7. Means for regulating the flow of oil to an oil burner comprising an oil chamber having an inlet, a float controlled valve controlling flow through said inlet, the chamber having an outlet, a longitudinally movable valve having a stem and controlling flow through said outlet, adjustable means to limit the movement of the valve toward its seat, the valve stem having a pair of stops spaced from each other, thermostatically operated means for shifting said valve toward or from its seat including a thermostat having an arm, 100 the arm loosely engaging the valve stem between the stops, and means for adjusting the thermostat, the thermostat being mounted upon the exterior of the oil containing chamber. 95
